UNITED STATES PATENT OFFICE.

ALEKSANDER SERAFIN, OF UTICA, NEW YORK.

COMBINED SWORD AND PISTOL.

1,248,932.

Specification of Letters Patent.

Patented Dec. 4, 1917.

Application filed September 12, 1917. Serial No. 190,988.

To all whom it may concern:

Be it known that I, ALEKSANDER SERAFIN, a citizen of Russia, residing at Utica, in the county of Oneida and State of New York, have invented certain new and useful Improvements in Combined Swords and Pistols, of which the following is a specification.

This invention relates to certain new and useful improvements in combined swords and pistols.

The primary object of the present invention is to combine in a single structure, a sword and pistol, wherein a pistol or revolver of ordinary construction is capable of being only slightly modified to be provided with the particular form of sword and hand guard herein disclosed.

A further object of the invention is to provide in a single structure, a combined sword and pistol wherein the sword blade is pivotally mounted to the gun frame and fixed to the gun barrel and cartridge carrier so that in breaking down the gun, the sword is also lowered, the particular construction of hand guard facilitating this movement.

With the above objects in view and others that will appear as the nature of the invention is better understood, the same consists in the novel construction, combination and arrangement of parts hereinafter more fully described, illustrated in the accompanying drawings, and then claimed.

In the drawings forming a part of this application, and in which like designating characters refer to corresponding parts throughout the several views:—

Figure 1 is a side elevational view of the combined pistol and sword constructed in accordance with the present invention, with the sword blade partially broken away, and showing in dotted line position the gun and sword as broken down.

Fig. 2 is a cross sectional view taken upon line II—II of Fig. 1 showing the manner of connecting the sword blade to the hand guard.

Fig. 3 is a detail sectional view of a portion of the two-part hand guard showing the latch connection between the adjacent ends thereof.

Fig. 4 is a view similar to Fig. 3, showing the hand guard sections moved on their piv-

otal connection and with the latch disengaged, and

Fig. 5 is a top plan view of the form shown in Fig. 3, and partially shown in section, better to illustrate the spring-pressed latch for retaining the hand guard sections in locked positions.

Referring more in detail to the accompanying drawing, and particularly to Fig. 1, the reference numeral 10 designates the frame portion of a revolver having a handle stock 11 and a barrel portion 12 pivotally connected to the frame 10 in the usual manner and carrying the cartridge magazine 13.

The forward portion of the pistol frame 10 is bifurcated to provide a pair of ears 14 between which a depending plate 15 carried by the barrel 12 is pivotally mounted upon the pin 16.

The plate 15 has depending spaced arms 17 shown more clearly in Figs. 1 and 2 and between which arms 17 the rear end of the sword blade 18 is positioned and retained by the transverse fastening members 19 passing therethrough.

A hand guard is provided for the sword blade 18, the same being formed of two members 20 and 21 hingedly connected as at 22 at a point substantially midway the ends thereof while the rear attaching end of the section 21 is pivotally connected as at 23 to the stock 11 of the pistol. As shown in Figs. 1 and 2, the forward end of the hand guard portion 20 is pivotally connected as at 24 between the depending lower ends of the plate arms 17. In order to hold the hand guard sections 20 and 21 in their locked position as shown in Fig. 1 there is provided a latch member shown in Figs. 3 to 5, said latch including a spring-pressed bolt 25 engaged at its rear end by the spring 26 arranged in the socket 27 provided in the hand guard section 20 while the nose end 28 of said latch is adapted to be received in the socket or keeper opening 29 in the adjacent end portion of the hand guard section 21.

As shown in Figs. 3 to 5, the hand guard section 20 is provided with a transverse slot 30 through which a pin 31 connected to the latch 25 is adapted to project and is provided upon the opposite protecting ends thereof with operating heads 32.

From the above detail description of the

construction of the device, it is thought that the operation thereof will be at once apparent, it being noted that in breaking down the gun, the bolt 31 is moved against the tension 5 of the spring 26 by shifting the heads 32 thereof, which action releases the operative end 28 of said latch from the keeper socket 29, and by pulling downwardly upon the gun barrel 12 or sword blade 18 the hand guard 10 sections 20 will move to the dotted line position shown in Fig. 1, as will also the barrel and sword.

While the form of the invention herein shown and described is what is believed to be the preferred embodiment thereof, it is nevertheless to be understood that various forms, modifications, and arrangements of parts may be made without departing from the spirit and scope of the invention as 20 claimed.

What I claim as new is:

1. A combined sword and pistol including a pistol and a sword, a hand guard for the sword connected at its upper ends to the 25 sword and pistol, said guard being formed of hinged sections.
2. A combined sword and pistol including a pistol and a sword, a hand guard for the sword connected at its upper ends to the 30 sword and pistol, said hand guard being formed of hinged sections and the outer ends thereof pivotally connected to the sword and pistol.
3. A combined sword and pistol including a pistol and sword, a hand guard for the 35 sword connected at its upper ends to the sword and pistol, said guard being formed of hinged sections, and a latch connection between the adjacent ends of the hinged sections.
4. A combined sword and pistol including a pistol and a sword, a hand guard for the sword connected at its upper ends to the 40 sword and pistol, said hand guard being

formed of hinged sections and the outer ends 45 thereof pivotally connected to the sword and pistol, and a latch connection between the adjacent ends of the hinged sections.

5. A device of the class described comprising a pistol, a pair of ears carried thereby, the pistol barrel having a plate pivotally mounted in said ears, a pair of arms depending from said plate, a sword blade fixed between said arms, and a hand guard extending between the lower ends of said arms and 55 the stock of the pistol.

6. A device of the class described comprising a pistol, a pair of ears carried thereby, the pistol barrel having a plate pivotally mounted in said ears, a pair of arms depending from said plate, a sword blade fixed between said arms, and a two part hinged hand guard extending between the lower ends of 60 said arms and the stock of the pistol.

7. A device of the class described comprising a pistol, a pair of ears carried thereby, the pistol barrel having a plate pivotally mounted in said ears, a pair of arms depending from said plate, a sword blade fixed between said arms, and a two-part hand 70 guard pivotally connected at its ends to the lower ends of said arms and the stock of the pistol.

8. A device of the class described comprising a pistol, a pair of ears carried thereby, the pistol barrel having a plate pivotally mounted in said ears, a pair of arms depending from said plate, a sword blade fixed between said arms, and a two-part hinged hand guard pivotally connected at its ends to the 80 lower ends of said arms and the stock of the pistol, a tensioned sliding latch carried by one section of the hand guard, the other section of the hand guard having a recess adapted to receive said latch and operating 85 means therefor.

In testimony whereof I affix my signature.
ALEKSANDER SERAFIN.
